UNITED STATES PATENT OFFICE.

WILLIAM A. MANGLESS, OF CHICAGO, ILLINOIS, ASSIGNOR TO AMERICAN AUTOMATIC PRODUCTS CORPORATION, OF CHICAGO, ILLINOIS, A CORPORATION OF ILLINOIS.

DESIGN FOR A PHONOGRAPH-CABINET.

54,857.

Specification for Design.

Patented Apr. 13, 1920.

Application filed November 28, 1919. Serial No. 341,338. Term of patent 14 years.

To all whom it may concern:

Be it known that I, WILLIAM A. MANGLESS, a citizen of the United States, residing at Chicago, in the county of Cook and State of Illinois, have invented a new, original, and ornamental Design for a Phonograph-Cabinet, (D,) of which the following is a specification, reference being had to the accompanying drawing, forming a part thereof.

The figure is a perspective view of a phonograph cabinet showing my new design.

I claim:

The ornamental design for a phonograph cabinet as shown.

WILLIAM A. MANGLESS.

Witness:

HENRY H. KOVEN.
